UNITED STATES PATENT OFFICE

JOHN L. BLASDELL AND COBURN H. DERRINGER, OF VENTURA, CALIFORNIA

DESIGN FOR A COMBINED LAMP AND SMOKING STAND

Application filed December 28, 1929. Serial No. 33,972. Term of patent 3½ years.

To all whom it may concern:

Be it known that we, JOHN L. BLASDELL and COBURN H. DERRINGER, citizens of the United States, and residents of Ventura, Ventura County, California, have invented a new and original Design for a Combined Lamp and Smoking Stand, of which the following is a specification, reference being had to the accompanying drawing, forming a part hereof.

Figure 1 is a side elevation of the article.

Figure 2 is a plan showing a rectangular top or hood within which is a smaller, concentric frame enclosing a smaller, concentric dish-like part. A finial element of inverted U-shape rises above the dish-like part, and

the top of the lamp column is surrounded by a shade or fringe whose shape is rectangular and conforms to the outer hood. Parallel, more or less elliptical ornaments lie across the top finial bar, and intermediate of the height of the column is an ornamental, rectangular cornice or belt.

What is claimed is:

The ornamental design for a combined lamp and smoking stand, substantially as shown and described.

Signed at Los Angeles, California, December 18, 1929.

J. L. BLASDELL.
C. H. DERRINGER.
